UNITED STATES PATENT OFFICE.

ALARIC R. TUCK, OF PROVIDENCE, RHODE ISLAND.

DESIGN FOR AN EMBLEM.

No. 39,945.

Specification for Design.

Patented May 4, 1909.

Application filed February 11, 1909. Serial No. 477,477. Term of patent 7 years.

To all whom it may concern:

Be it known that I, ALARIC R. TUCK, a citizen of the United States of America, residing at Providence, in the county of Providence and State of Rhode Island, have invented a new, original, and ornamental Design for an Emblem, of which the following is a specification, reference being had to the accompanying drawing, forming a part thereof, which represents a front view of an emblem showing my new design.

I claim:

The ornamental design for an emblem, substantially as shown.

ALARIC R. TUCK.
